UNITED STATES PATENT OFFICE.

FRED A. POOR, OF CHICAGO, ILLINOIS, ASSIGNOR TO THE P & M COMPANY, OF CHICAGO, ILLINOIS, A CORPORATION OF ILLINOIS.

RAIL-ANCHOR.

1,318,107.

Specification of Letters Patent.

Patented Oct. 7, 1919.

Original application filed February 13, 1918, Serial No. 216,847. Divided and this application filed October 16, 1918. Serial No. 258,407.

To all whom it may concern:

Be it known that I, FRED A. POOR, a citizen of the United States, residing at Chicago, in the county of Cook and State of Illinois, have invented certain new and useful Improvements in Rail-Anchors, of which the following is a specification.

My invention relates to a device for preventing railroad rails from creeping longitudinally, and has for its primary object to provide a novel and improved device of this type which will be simple in construction, inexpensive to manufacture, and easily applied to the rail, and which will act to prevent the rail from creeping in either direction; an anti-creeping device having this latter characteristic being desirable for use on single track roads where the traffic runs in opposite directions, or in other situations in which the rail tends to move sometimes in one direction and sometimes in another.

The invention consists in the novel arrangements, constructions and combination of parts hereinafter described and claimed for carrying out the above stated objects, and such other objects as may appear from the following specification.

The invention is illustrated in a preferred embodiment in the accompanying drawings, 30 wherein:

Figure 1 is a view in perspective of a rail anchor constructed in accordance with my invention, applied to a railroad rail;

Fig. 2 is a plan view of the structure shown in Fig. 1;

Fig. 3 is a detail plan view of a spring member employed in my preferred embodiment;

Fig. 4 is a view in elevation, looking toward the inside of the rigid or shoe member employed in connection with the spring member shown in Fig. 3;

Fig. 5 is an edge view of the spring member, showing the normal set of the spring before it is applied to its operative position on the rail;

Fig. 6 is a side view, in elevation, of a rail with my rail anchor applied in operative position thereto;

50 Fig. 7 is a view similar to Fig. 6, shown on a larger scale, and illustrating the spring

member of my device in process of application to the rail; and

Fig. 8 is a sectional view on a reduced scale, taken on line 8—8 of Fig. 6, looking 55 in the direction indicated by the arrows.

Like characters of reference designate like parts throughout the several figures of the drawings.

Referring to the drawings, 10 designates 60 a railroad rail and 11, 11^a two adjacent cross ties on which the rail is supported. My preferred form of rail anchor as illustrated in this figure preferably consists of a shoe or rigid member 12 and a yoke member 13, 65 which together embrace the base flange of the rail and have an interlocking engagement with each other which maintains these members in their operative position on the rail. The shoe or rigid member 12 consists 70 of a metal bar which engages the upper inclined surface of the base flange A of the rail base, and is formed at each end with tie engaging lugs 14, 14^a. These lugs are preferably formed with shoulders which fit over 75 the vertical edge of the base flange of the rail and are formed with apertures which receive spikes 15 for spiking this member to the top surface of two adjacent ties. The rigid member 12 is provided at the center 80 with a depending flange 16 which is recessed, as indicated at 17 (Fig. 4), to receive the body portion of the yoke 13, and is formed with a boss 19 which provides a supporting shelf 18 for holding the spring yoke member 13 in its operative position, as will be 85 hereinafter described.

The web 16 of the rigid member is also formed on each side of the recess 17 with inwardly projecting lugs 20, 21, which extend 90 underneath the rail base and provide a rail base engaging jaw 22 which engages the base flange A of the rail at a point where the said rigid member has its interlocking engagement with the spring yoke 13. By having the spring yoke interlock with the rigid member adjacent the jaw 22, the yoke may be secured tightly on the base flange of the rail without danger of springing or distorting the relatively long bar 12.

100 The yoke member 13 is preferably made of spring steel, and is formed at one end

with a jaw 23 which engages the edge of the rail base opposite the jaw 22 of the rigid member and is formed with an angularly disposed hook portion 24 which is forced 5 into a biting engagement with the upper surface of the flange B of the rail base when the anchor device is applied to the rail and is in its operative position. The spring yoke is formed at the other end with an enlargement 10 25 which extends around the jaw portion of the rigid member 12 and interlocks therewith when the yoke and the rigid member are in operative position on the rail. The portion of the yoke which extends under the 15 rail is preferably given a slight set or twist, as indicated in Figs. 3 and 5, so that the enlargement 25 will normally stand at a slight angle with relation to the jaw 23. When the rigid member 12 and the yoke 13 are in 20 operative position on the rail, the body portion of the yoke adjacent the enlargement 25 extends into the recess 17 of the rigid member, the lower edge of the yoke being cut away, as indicated at 26 and seating on the 25 shelf 18.

When applying the yoke 13 to its interlocked position with the shoe 12, as indicated in Figs. 1, 2, 6 and 8, the yoke is subjected to a torsional strain by twisting the 30 same from its normal set position, as indicated in Figs. 3 and 5, to the position indicated in Figs. 1, 2, 6 and 8. This twisting operation may be accomplished by any suitable means, such, for example, as by use of 35 the claw bar or wrench 27 which may be applied over the enlargement 25.

28 designates a boss on the wrench to engage the projecting boss 19 and provides a suitable fulcrum for the wrench when 40 springing the yoke from its normal position, as indicated in Fig. 7, to the position shown in Fig. 6. The yoke 13, in addition to being twisted, is raised so that when in operative 45 position, the upper end of the enlargement 25 will extend back of a lug 29 formed on the rigid member. By straining the yoke 13 as above mentioned, the jaw end of the yoke is rocked rearwardly so that the angularly disposed lip 24 of the jaw 23 will exert a 50 downward pressure against the upper surface of flange B of the rail base. The tendency which the spring yoke has when in this position to return to its normal or twisted position exerts a spring pressure 55 against the end of the lug 29. This pressure prevents vibration of the rail from dislodging the yoke from its seat on the shelf 18, or appreciably lessening its effective grip on the base flange of the rail. The spring yoke, 60 when applied in operative position, preferably stands at substantially right angles to the rigid member 12 at a point opposite the jaw portion 22, so that any longitudinal movement of the rail in either direction 65 tending to change the angular relation of

these members will increase the grip of the device on the rail base.

This application is a division of my co-pending application, Serial No. 216,847, filed February 13, 1918. 70

I claim:

1. A rail anchor adapted to resist longitudinal movement of a rail in either direction, comprising a rigid member adapted to be secured to the top face of adjacent ties 75 on which the rail is supported and a spring member having an interlocking engagement with each other, and which, together embrace the base of the rail.

2. A rail anchor adapted to resist longitudinal movement of a rail in either direction, comprising a rigid member which fits over one edge of the rail base and is adapted to be secured to the top face of a tie, and a spring member formed with a jaw which 85 fits over the opposite edge of the rail base and is adapted to have an interlocking engagement with the said rigid member.

3. A rail anchor adapted to resist longitudinal movement of a rail in either direction, comprising a rigid member formed with a rail base engaging jaw which fits over one edge of the rail base and is adapted to be secured to the top face of a tie, and a spring member formed with a jaw which fits over 95 the opposite edge of the rail base and is adapted to have an interlocking engagement with the said rigid member.

4. A rail anchor adapted to resist longitudinal movement of a rail in either direction, comprising a rigid member and a spring member having an interlocking engagement with each other, and which together embrace the base of the rail, said rigid member extending from one of the ties on which the 100 rail is supported to the next adjacent tie and being adapted to be secured to the upper faces of said ties.

5. A rail anchor comprising a shoe member and a spring member provided with jaws 110 adapted to engage opposite edges of the base flange of a rail, one of said members being adapted to be spiked to adjacent ties to resist longitudinal movement of the rail in either direction.

6. A rail anchor comprising a shoe member and a spring member provided with jaws adapted to engage opposite edges of the base flange of a rail, one of said members being 115 adapted to be secured to adjacent ties to resist longitudinal movement of the rail in either direction.

7. A rail anchor comprising a shoe member which fits over one edge of a rail base and is adapted to be secured to adjacent ties, 120 and a spring member engaging the opposite edge of the rail base and having an interlocking engagement with said shoe member.

8. A rail anchor comprising a bar formed near its middle with a jaw adapted to fit 125

130

over one edge of a rail base and adapted to have its opposite ends secured to adjacent ties, and a spring member engaging the opposite edge of the rail base and having an 5 interlocking engagement with said rigid member.

9. A rail anchor comprising a bar formed near its middle with a jaw adapted to fit over one edge of the rail base and adapted 10 to have its opposite ends secured to the top faces of adjacent ties, and a spring member engaging the opposite edge of the rail and having an interlocking engagement with said rigid member.

15 10. A rail anchor comprising a rigid member secured to two adjacent ties and formed with a jaw which fits over one edge of the base of a rail, and a spring member engaging the opposite edge of said base and having 20 an interlocking engagement with said rigid member adjacent said jaw, said spring member being adapted to be strained in its application to the rail.

25 11. A rail anchor comprising a rigid member secured to adjacent ties and formed with a jaw which fits over one edge of the base of a rail, and a spring member engaging the

opposite edge of said rail base and having an interlocking engagement with said rigid member, said spring member being subjected to a torsional strain in its application 30 to the rail.

12. A rail anchor comprising a bar formed near its middle with a jaw adapted to fit over one edge of a rail base, and adapted 35 to have its opposite ends secured to adjacent ties, and a spring member formed with a jaw which engages the opposite edge of the rail base and with an enlargement having an interlocking engagement with said 40 bar adjacent said jaw; said spring member being subjected to a torsional strain in its application to the rail.

13. A rail anchor comprising a rigid member formed with a rail base engaging jaw 45 and with lugs adapted to be spiked to the top faces of two adjacent ties, and a spring yoke formed with a jaw which engages the opposite edge of the rail base and with an enlargement having an interlocking engagement with said rigid member; said spring yoke being subjected to a torsional strain 50 when applied to the rail.

FRED A. POOR.
